BOX STACKING MECHANISM

Bruner R. Daves and Warren L. Irvine,
Claremont, Calif.

Application November 22, 1946, Serial No. 711,524

16 Claims.

(Cl. 214—6)

1

This invention relates to means for receiving successive ones of a plurality of boxes and arranging the same in vertically stacked relation, and pertains more particularly to a device which will receive the successive boxes and place them successively at the bottom of a stack which is being formed, until the desired number of boxes in the stack have been arranged, and then cause the assembled stack to be discharged from the device as a unit.

One of the particular objects of this invention is to provide a device which will arrange a plurality of boxes in stacked relation without excessive jarring or disturbance of the contents of the boxes, a feature of particular importance where the device is employed to stack boxes of oranges or other fruit which are subject to decay and spoilage in the event of bruising.

A further object of the invention is to provide a device of the character described, which may be utilized in close association with a delivery conveyor in position to receive boxes delivered thereby, to receive and arrange such boxes in stacked relation, and deliver the stacked assembly, in a substantially automatic fashion.

In the handling of boxes containing fruit, such as oranges, it is necessary in the conservation of space to stack the boxes to as great a height as may be accomplished by manual labor, and where the boxes have not been "lidded," i. e. the "pack" made secure, the fruit is necessarily loose and is subject to dislodgment to a level above the top of the box as a box is literally thrown on top of a fairly high stack. When the next box is tossed on top of a box containing such dislodged fruit, the fruit projecting above the top of the box is subject to bruising and consequent rapid spoilage. In view of this type of difficulty in the handling of boxes containing loosely packed fruit, it is a particular object of this invention to provide a device which will form a stack of boxes by placing the succeeding boxes at the bottom of the stack as it is being formed, under conditions such that the bottom box in process of stacking is never subjected to forces or movement such as to dislodge the fruit from the position it occupies when delivered to the stacking device, thereby avoiding fruit damage of the type above described.

The device of the present invention may comprise, in general, a guide means defining a vertically extending hollow shaft having internal transverse dimensions consonant with the transverse dimensions of the boxes to be stacked and provided adjacent its lower end with an opening through which the boxes may be supplied in succession at a given loading level, together with carriage means adapted to receive a so-delivered box and raise the same upwardly within the hollow shaft to a locating level. The device further comprises means for returning the carriage to the loading level for the reception of a second box, carrying such second box upwardly

10 into contact with the first box disposed at the locating level and thereafter raise the first box and the second box in a stacked relationship until the second box is disposed at the locating level. Means are provided for repeating this procedure until the desired number of boxes have been disposed in stacked relation, after which the entire stack is lowered to the floor or any other suitable level for discharge from the shaft as an assembled stack.

15 Other features of the invention will be brought out in the ensuing specific description of a typical embodiment, or will be apparent from such description. The accompanying drawings illustrate this typical embodiment in detail, and referring thereto:

Fig. 1 is a three-quarter view of the stacking device of this invention, taken from the loading side;

Fig. 2 is a three-quarter view taken from the discharge side;

Fig. 3 is a partly broken away vertical section as taken on line 3—3 of Fig. 2;

Fig. 4 is a fragmentary vertical section in the same plane as the left side of Fig. 3, taken in the vicinity of line 6—6 in Fig. 3, showing a position adopted by the boxes during the stacking operation;

Fig. 5 is a view corresponding to Fig. 4 showing an alternative position adopted by the boxes;

Fig. 6 is a fragmentary transverse section as taken on line 6—6 in Fig. 3;

Fig. 7 is a fragmentary vertical section as taken on line 7—7 in Fig. 3;

Fig. 8 is a fragmentary transverse section as taken on line 8—8 in Fig. 6;

Fig. 9 is a fragmentary vertical section as taken on line 9—9 of Fig. 3;

Fig. 10 is a diagrammatic showing of one side of the stacking device showing the relative location of operating circuit control switches which may be employed to secure a substantially automatic operation of the device; and

Fig. 11 is a schematic showing of a form of control circuit which may be employed for operation of the stacking device of this invention.

Referring to the drawings, the device may comprise a plurality of vertical members 1 arranged to define a vertically extending shaft 2 having internal dimensions consonant with the transverse dimensions of the style of box which is to be handled in a stacking operation. The drawings show various boxes in process of being stacked, which are indicated generally by the reference numeral 3.

The members 1 are mounted on or secured to a floor structure 4 above a chain conveyor 5 having an active run located slightly above the floor level in position to carry away a stack of boxes lowered thereupon; such chain conveyors being in common use in packing houses, no detailed showing thereof is made herein. At a suitable height above the floor, as may be required for

cooperation with a particular conveyor assembly, the side of the shaft 2 is cut away to provide a receiving opening 6 through which boxes may be passed from an adjacent conveyor 7. Usually a main conveyor will be provided as at 8 which will carry boxes to any given stacking device, and the conveyor 7 will be employed to receive the boxes from the main conveyor 8 and to carry them to the shaft 2.

Within the shaft 2 a vertically movable carriage is provided for the purpose of receiving the boxes delivered through the opening 6, and this carriage may comprise a pair of spaced platform members 9 threadedly mounted on lead screws 10 at the respective sides of the structure, the lead screws being journaled at their bases as at 11 and provided with power operating means 12 which may conveniently be located at the upper end of the frame defined by the uprights 1. Each of the platform members is provided with a plurality of supporting rollers 13 so positioned as to underlie the respective longitudinal ends of the nether surface of the box 3 delivered from the conveyor 7 through the opening 6. Suitable guide rollers 14 may be provided for engagement with the adjacent uprights 1, to cause the platform members 9 to be constrained in relative position during the rotation of the lead screws 10 in the operation of the device.

When a box is delivered from the conveyor 7 through the opening 6 onto the carriage means defined by the platform members 9, the operating means 12 is caused to be energized in such direction as to move the carriage means upwardly in a start of the stacking operation. Referring to Fig. 3 in particular, the box received by the carriage means is caused to be carried upwardly to approximately one and one-half box heights, adjacent which level means are provided for supporting the box against downward movement while the carriage means is lowered to the loading level as defined by the conveyor 7. Such supporting means, hereinafter referred to as locating means, is of a character such as to be readily moved out of locating position with respect to a superior box when a succeeding box is raised toward locating position. By way of example, we have illustrated such locating means as comprising a plurality of locating rollers 15 mounted on suitable brackets 16 attached to the respective corners of the framework defining the shaft 2 and adapted to engage a box at its four corners. These rollers are carried by axial pins 17 located in guide slots 18 so shaped as to permit upward and outward movement of the rollers upon engagement by the upper edges of an inferior box, the amount of movement permitted by the guide slots 18 being such as to locate the inwardly directed peripheries of the rollers 15 inwardly of the ends of the box 3 in their lowered position and outwardly of the ends of the box in their raised position. The slots 18 are preferably provided with vertically extending inner end portions 18a adapted to resist outward movement of the rollers 15 under the load imposed by a box 3' (Fig. 3).

We preferably provide means for lifting the rollers 15 clear of the boxes 3 to a position such as they will not interfere with the lateral discharge of a stack from the shaft 2 as hereinafter described, and such means may comprise a solenoid 19 mounted on each of the brackets 16 and having an actuating rod 19a carrying a foot 20 adapted to engage the lower edge of the roller 15, the solenoid being mounted on the outside of

5 the bracket and extending into the space within the bracket into engagement with the roller 15 through a slot 16a in said bracket. This structure is omitted in Figs. 1, 2, 4, and 5, shown in small scale sectionally and in elevation in Fig. 3, and shown in greater detail in Figs. 6 and 8. Operation of the solenoid 19 is adapted to cause the roller 15 to adopt the dot-dash position of Fig. 8. It is not necessary that the solenoid be of sufficient strength to pull the roller 15 out from under a located box 3', inasmuch as it is only necessary to lift the rollers 15 clear of a box when the roller-box relation is that of Fig. 4.

When the carriage means is raised to place a 15 box on the locating rollers, the rollers move upwardly and laterally after the manner shown in Figs. 4 and 8, and when the nether edges of the box clear the rollers, the rollers drop inwardly in position to be engaged by the corners of the 20 box as the carriage means is returned toward the loading level, as shown in full lines in Fig. 8. When a box has already been located on the rollers 15, the next succeeding box will engage the rollers (see dot-dash lines 3'' in Fig. 8) and push them out of contact with the box which they had been supporting, and the box or boxes above the position of the rollers will fall against the upper edge of this next succeeding box. The 25 continued upward movement of the carriage means then carries the whole stack upwardly until the lower edge of the lowest box clears the rollers 15, as to the position of Fig. 5, at which time the carriage means is lowered until the bottom corners of such box engage and are located 30 by the rollers, after which the carriage means is returned to the loading level.

Assuming that the boxes are to be stacked 35 nine in a stack (a height commonly in use in citrus packing houses), only eight boxes have to be carried as high as the locating level defined by the rollers 15 inasmuch as the ninth box has merely to be carried upwardly an amount sufficient that the rollers 15 are pushed out of the way and the top eight boxes released into engagement with the top of the ninth box. (To conveniently control the operating drive mechanism 40 12, circuit control means can be located in position to be engaged by the top box of a series instead of requiring the carriage means to be raised past the locating rollers to the locating level, as will hereinafter more particularly be described.) After the desired number of boxes have been placed in stacked relation, the entire 45 stack is then lowered by lowering the carriage means clear to the floor so that the bottom box of the stack (as shown in dot-dash lines at 3a in Fig. 3) is brought into contact with the chain conveyor 5. The downward movement of the platform members 9 is preferably slightly greater 50 than that just sufficient to place the bottom wall of the bottom box on the conveyor 5, so as to insure that there will be no opposition to the withdrawal of the stack.

Inasmuch as the stack is withdrawn as a unit, 55 we preferably provide movable guide means or gates 21 at the rearward side of the shaft 2, which will function to retain the stacked boxes within the shaft 2 until it is desired to remove the stack as a unit, and these gates 21 may be pivotally mounted on the rearward frame members 1, as at 22, and may be operated through the agency of a gear and crank assembly 23 located below the floor level and operated by a lever arm 24 which is engageable by the bottom box of the 60 stack as the stack is lowered to the position shown

in dot-dash lines in Fig. 3. This gate-operating mechanism is illustrated in greater detail in Fig. 9, and may comprise the lever 24 which is linked through arm 25 to a bell crank 26 carried on a transverse shaft 27 carrying a bevel gear 28 meshing with a bevel gear 29 carried on an operating shaft 31 secured to one of the gates 21, it being appreciated that a drive assembly for each of the gates may be provided, or that one of the gates may be direct-driven and the other operated by a linkage mechanism.

When the stack of boxes has been withdrawn from the shaft 2 by the chain conveyor 5, the lever 24 will be returned to the full line position of Fig. 9, as through the agency of an operating spring 32, and this return movement may be utilized to institute upward movement of the carriage means to the loading level.

The drive means 12 is illustrated as comprising a reversible electric motor 33 driving a cross shaft 34 which is geared to the operating or lead screws 10 at gear boxes 35. Fig. 11 shows one form of operating circuit which may be employed to secure a fully automatic operation of the stacking mechanism, although it will be appreciated that the device may be manually operated by the provision of conventional "up" and "down" switches available to the operator who is responsible for selecting a particular type of box off the conveyor 8 and causing it to move over the conveyor 7 into the shaft 2. Fig. 10 represents the location of a plurality of switches which are operable by the carriage means or the boxes in the stack, S_1 representing a normally open double-pole switch located so as to be actuatable by a box 3 when it is received by the carriage means after delivery from the conveyor 7. It is intended that this switch will remain in closed or operated condition so long as a box is present on the carriage means. S_2 represents a double-pole switch having a set of normally closed contacts and a set of normally open contacts located so as to be operable by one of the platform members 9 when the carriage means is raised to a position such as that shown in Fig. 5 in which the bottom of a box being stacked is raised above the level of the rollers 15. S_3 is a double-pole normally closed switch which may be located in position to be actuated (opened) by one of the platform members as when the carriage means reaches the loading level, i. e. when the rollers 13 are aligned with conveyor 7. S_4 is a double-pole switch comparable to that employed at S_2 , i. e. having a pair of normally closed and a pair of normally open contacts, which is positioned near the top of the shaft 2 where it is actuatable by the top edge of a stack which has been brought to the desired height by the placement of the last box on the bottom. As brought out above it is unnecessary that the carriage means be raised as high for the engagement of the top of the stack upon switch S_4 as it is to locate a box on the locating rollers 15, it being necessary only to raise the bottom box high enough to clear the locating rollers from under the next superior box (Fig. 4 illustrating such a position), and then continue the upward movement enough to carry the stack of boxes upwardly a short distance into contact with S_4 . S_5 may comprise a four-pole switch having three sets of normally closed contacts and one set of normally open contacts, and is preferably located so as to be engageable by one of the platform members 9 in its lowermost position (such as that indicated in dot-dash lines in Fig. 3). S_6 may comprise a

single-pole normally open switch actuatable by the lever 24 at a point intermediate the full line and dot-dash line positions thereof shown in Fig. 9.

In the illustrated circuit arrangement, three relays R_1 , R_2 and R_3 are provided, R_1 controlling the "up" movement of the carriage, R_2 controlling the "down" movement, and R_3 being utilized in the operation of lowering the stack onto the conveyor 5.

At the start, with the carriage at the loading level, all relays R_1 , R_2 and R_3 are inoperative. When a box enters the carriage defined by the platform members 9, S_1 is closed, connecting line lead 51 through lead 52 through upper normally closed contacts of S_5 to energizing side of R_1 , at contact 53, thence through contact 54, line 55 to coil 56, thence through line 57, normally closed contacts of switch S_2 , line 58, the lower normally closed contacts of S_3 and contacts 59 of S_4 , through line 60 to control contact 61 of R_2 , thence through line 62 to line lead 63. This energizes R_1 , causing line lead 51 to be connected through line 64, jumper 65, contact 66, line 67, thermal relay TR_1 , coil 68 of "up" control switch assembly 69, thence to line lead 63. The coil 56 is then connected, by operation of R_1 , through movable contact 70 of the "make-before-break" combination 70—53, 54, direct to line 64 which is connected to line lead 51, holding the relay R_1 closed independent of S_1 so long as S_2 and S_4 remain closed. When the carriage is at the loading level, S_3 is held open, and the lower (normally closed) contacts thereof hold open the return circuit for coil 56 inasmuch as the latter contacts are in series with S_2 . For this reason a lower set of normally open contacts are provided for S_1 in position to shunt the latter contacts of S_3 until the carriage has moved upwardly a sufficient amount to close S_3 .

Operation of motor M in an "up" direction raises the carriage and its box until the bottom of the box has been carried above the locating rollers 15, at which position switch S_2 is engaged, opening the upper pair of contacts and closing the lower pair. Opening the upper pair of contacts opens the return circuit for the coil 56 of R_1 , opening the supply lead at 66 and stopping motor M . Closing the lower contacts of S_2 , connects line lead 51 through line 71 to the energizing contact 72 of R_2 , thence through contact 73, line 74 to coil 75, thence through line 76 to control contact 77 on R_1 , through lines 78 and 79 through the upper normally closed contacts of S_3 to line lead 63. Operation of R_2 closes the circuit to "down" switch 80, from line lead 51 through leads 81 through the lowermost normally closed contacts of S_6 , through jumper 82, contact 83 and lead 84 to thermal relay TR_2 , thence to coil 85, causing the motor M to run in the "down" direction. This lowers the carriage away from the first box located on the locating rollers 15, and returns it to loading position, at which time S_3 is opened, opening the return circuit for coil 75 of R_2 , and de-energizing motor M .

The device is now in condition for receiving the second box within the carriage, which closes S_1 and causes a repetition of the operation. Two boxes are now supported on the locating rollers, the first resting on top of the second. After a given number of such repetitions, so that a desired number of boxes, say eight, have been supported upon the locating rollers, and the ninth box is received by the carriage, the resulting

upward movement of the carriage, after engagement of the bottom of the eighth box by the top of the ninth, causes the top of the first box (on top of the stack) to engage S_4 . Operation of S_4 opens contacts 59 , opening the return circuit for coil 56 of R_1 , stopping the upward travel of the assembly. Operation of S_4 also causes the lower normally open contacts to close, connecting line lead 51 through leads 86 to energizing contact 87 of R_3 , thence through contact 88 , lead 89 , coil 90 , lead 91 to the middle normally closed contacts of S_5 , and lead 92 to line lead 63 . Operation of R_3 causes contact 93 to close, connecting line lead 51 through leads 94 and 95 to energizing contact 72 of R_2 , causing the motor M to be operated in the "down" direction and lowering the carriage. Upon operation of R_3 , contacts 96 close before contacts 87 and 88 open, and hold R_3 by connection direct to line lead 51 through lead 94 so that de-operation of S_4 will not interrupt the downward travel of the carriage. Operation of R_3 also closes contact pair 97 of R_3 connecting solenoids L_1 , L_2 , L_3 and L_4 across line leads 51 and 63 , lifting the locating rollers 15 to their upper most positions, clear of the stack. Solenoids L_1 — L_4 represent the solenoids shown at 19 in the drawings. Contacts 98 shunt the upper normally closed contacts of S_3 , so that opening of S_3 will not cause R_2 to be de-energized when the loading level is reached by the carriage, which therefore descends to its lowermost position (dot-dash lines in Fig. 3), where S_5 is operated. Operation of S_5 opens the return circuit for coil 90 , at 91 — 92 , de-operating R_3 , which in turn de-operates R_2 and stops motor M . Inasmuch as it is preferred that the locating rollers 15 remain out of engagement with the stack of boxes at this lowered position, S_5 is preferably provided with a lower normally open set of contacts 99 which close to shunt contacts 97 and retain energization of solenoids L_1 — L_4 .

When the stack is lowered to this lowermost position of the carriage, opening gates 21 by operation of the gear and crank assembly 23 , the floor chain conveyor 5 carries the stack away, and as the lever 24 is released by removal of the stack, the switch S_6 is momentarily closed, connecting line lead 51 through leads 100 , normally closed contacts 101 , lead 102 and lead 103 to energizing contact 53 of R_1 , starting an upward movement of the carriage, relay R_1 holding through lead 64 and contact 70 . When the carriage leaves its lowermost position, it goes out of contact with S_5 , opening the circuit to the solenoids L_1 — L_4 .

As the carriage is brought up to loading position, S_2 is contacted, opening the lower set of normally closed contacts (in series with the normally closed contacts of S_2 and S_4) breaking the return circuit for coil 56 of R_1 and stopping the carriage. In this position there is no box present in the carriage, hence S_1 will not be operated and the shunt for the lower contacts of S_3 is not connected.

It will be appreciated that the specific structure herein shown and above described is to be considered as illustrative only, and not limitative upon our invention, the broad scope of our invention being defined in the subjoined claims. For example, while we have shown a preferred form of locating means to hold the stacked boxes in the shaft as comprising roller members 15 , numerous other forms of locating latches may be visualized by another skilled in such art, and

may be substituted therefor without departure from our broad concept of the structure.

We claim:

1. In a box stacker, the combination of: an elevator adapted to be reciprocated vertically between a box receiving position and an upper position to permit this to receive boxes and elevate the same in the formation of a stack; latch means for supporting said stack as it is thus progressively formed; means for delivering boxes horizontally in a given direction onto said elevator; means for receiving said stack from said elevator after it is formed and discharging it out of said stacker in the same direction as that in which said boxes were delivered to said stacker; a pair of gates disposed alongside opposite edges and in front of the path along which said elevator operates vertically, said gates acting as limit stops for individual boxes being fed onto said elevator and as stack guides; and means operating in timed relation with the delivery of said stack from said elevator onto said stack discharge means for displacing said gates from in front of said stack to permit the latter to be discharged from said stacker.

2. A combination as in claim 1 in which said stack discharge means comprises a conveyor onto which said elevator deposits said stack by travelling downwardly below its box receiving position, said means for displacing said gates being actuated by engagement with the lower end of said stack as the latter is lowered onto said conveyor.

3. In a box stacker, the combination of: an elevator adapted to be reciprocated vertically between a box receiving position and an upper position to permit this to receive boxes and elevate the same in the formation of a stack; latch means for supporting said stack as it is thus progressively formed; means for delivering boxes horizontally in a given direction onto said elevator; means for discharging said stack out of said stacker after it is formed; a pair of gates disposed in front of opposite edges of said stack as it is being formed to prevent said stack falling in the direction in which it is to be discharged from said stacker; and means operating in timed relation with the discharge of said stack from said stacker for displacing said gates from in front of said stack to permit the latter to be discharged from said stacker.

4. A combination as in claim 3 in which said means for displacing said gates is actuated by vertical movement of the completed stack.

5. A combination as in claim 3 in which said stack, after being formed, is lowered downwardly on said elevator onto said stack discharge means and in which said means for displacing said gates from in front of said stack is actuated by said stack as the latter is so lowered.

6. A combination as in claim 3 in which said means for displacing said gates from in front of said stack is actuated coordinately with the discharge of said stack from said stacker and just prior to the commencement of said discharge movement of said stack.

7. A combination as in claim 3 in which said gates are pivotally supported on vertical axes and are swung away from in front of said stack in displacing said gates to permit the stack to be discharged from the stacker.

8. In a box stacker, the combination of: an elevator adapted to be reciprocated vertically between a box receiving position and an upper position to permit this to receive boxes and elevate the same in the formation of a stack; latch means for

supporting said stack as it is thus progressively formed; means for delivering boxes horizontally in a given direction onto said elevator; means for discharging said stack out of said stacker, after it is formed; guide means for the ends and backside of said stack as it is being formed; guide means disposed in front of said stack as it is being formed to prevent said stack falling in a direction in which it is to be discharged from said stacker; and means operating in timed relation with the discharge of said stack from said stacker for displacing from in front of said stack said front guide means to permit said stack to be discharged from said stacker.

9. In a box stacker, the combination of: elevator means operating to form a stack in a given vertical path; means for discharging said stack out of said stacker after it is formed; front guide means disposed in front of said stack when the latter is being formed to prevent said stack falling in the direction in which it is to be discharged from said stacker; and means operating in timed relation with the discharge of said stack from said stacker for displacing said front guide means from in front of said stack to permit the latter to be discharged from said stacker.

10. In a box stacker, the combination of: elevator means operating to form a stack in a given vertical path; means for discharging said stack out of said stacker after it is formed; guide means disposed at the ends and backside of said stack for guiding the latter as it is being formed; front guide means disposed in front of said stack when the latter is being formed to prevent said stack falling in the direction in which it is to be discharged from said stacker; and means operating in timed relation with the discharge of said stack from said stacker for displacing said front guide means from a front of said stack to permit the latter to be discharged from said stacker.

11. In a box stacker the combination of: an elevator adapted to be reciprocated vertically between a box receiving position and an upper position to permit this elevator to receive boxes and elevate the same in the formation of a stack; latch means for supporting said stack as it is thus progressively formed; means for delivering boxes horizontally in a given direction to said elevator; a horizontal conveyor for discharging said stack out of said stacker after it is formed; front guide means disposed in front of said stack as it is being formed to prevent said stack falling in the direction in which it is to be discharged on said conveyor from said stacker; means responsive to the stack, being formed as aforesaid by said elevator, reaching a given height to release said latch means and to lower said elevator with said stack thereon to deposit said stack onto said conveyor; mechanism for disposing said front guide means away from in front of said stack; and a member, responsive to vertical movement of said completed stack on said elevator, to actuate said mechanism to dispose said front guide means away from in front of said stack.

12. A combination as in claim 11 in which said member is disposed beneath said stack and is engaged by said stack as it descends while being lowered onto said conveyor whereby said member is shifted to actuate said mechanism and dispose said front guide means away from in front of said stack.

13. A combination as in claim 11 in which said guide means comprise a pair of gates mounted

5 pivotally on axes disposed on opposite sides of said stack as the latter is being formed; and means normally swinging said gates into positions in front of said stack to guide the latter during its formation and prevent it falling in the direction in which it is to be discharged on said conveyor from said stacker, said member being responsive to vertical movement of said completely formed stack, to overcome said normally operative gate swinging means and swing said gates away from in front of said stack.

14. A combination as in claim 11 in which said guide means comprise a pair of gates mounted pivotally on axes disposed on opposite sides of said stack as the latter is being formed; and means normally swinging said gates into positions in front of said stack to guide the latter during its formation and prevent it falling in the direction in which it is to be discharged on said conveyor from said stacker, said member being responsive to vertical movement of said completely formed stack, to overcome said normally operative gate swinging means and swing said gates away from in front of said stack, said stack responsive member being mounted beneath said stack so as to be engaged by said stack and be shifted downwardly thereby as said stack is lowered onto said conveyor.

15. In a box stacker, the combination of: an elevator adapted to be reciprocated vertically between a box receiving position and an upper position to permit said elevators to receive boxes and elevate the same in the formation of a stack; latch means for supporting said stack as it is thus progressively formed; means for delivering boxes horizontally to said elevator; means for receiving said stack from said elevator, after it is formed, for discharging said stack from said stacker; guide means disposed in front of said stack, as it is being formed, to prevent said stack falling, during its formation, in the direction it is subsequently to be discharged; and means responsive to vertical movement of said elevator and stack in the stack completing reciprocation of said elevator, to displace said guide means from in front of said stack.

16. In a box stacker, the combination of: elevator means adapted to form a stack in a given vertical path; means for receiving said stack from said elevator, after it is formed, for discharging said stack from said stacker; guide means disposed in front of said stack as it is being formed to prevent said stack falling, during its formation, in the direction it is subsequently to be discharged; and means actuated by vertical movement of said elevator and stack, and operating between the completion of said stack and said discharge thereof, to displace said guide means from in front of said stack.
